Primary Examiner — Ricky Pham

(57) **CLAIM**

The ornamental design for a cookware assembly, as shown and described.

DESCRIPTION

FIG. 1 is a first perspective view of a cookware assembly showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the cookware assembly thereof;

FIG. 10 is an enlarged view of the selected portion 10 in FIG. 1; and,

FIG. 11 is an enlarged view of the selected portion 11 in FIG. 9.

The broken lines shown in the drawings depict portions of the cookware assembly that form no part of the claimed design.
